WALTER S. ELY, OF FLUSHING, NEW YORK.

REVOLVING-DOOR STRUCTURE.

1,007,025.

Specification of Letters Patent. Patented Oct. 24, 1911.

Application filed June 29, 1910. Serial No. 569,619.

To all whom it may concern:

Be it known that I, WALTER S. ELY, a citizen of the United States, and a resident of 18 Ash street, Flushing, borough of 5 Queens, and State of New York, have invented certain new and useful Improvements in Revolving-Door Structures, of which the following is a specification.

This invention relates to that class of 10 revolving doors in which the wings are made collapsible so that in case of emergency or panic they may all be pushed to one side of the central spindle so as to leave the passage open through the casing at both 15 sides of the spindle.

The invention consists of a particular means of connecting the door-wings to the spindle, a particular construction for the locks and braces connecting the wings 20 collapsibly, of automatically vibrated walls for the casing in place of the usual curved walls to contact with the revolving door-wings, of a special form of packing for the edges of the wings where they contact with the casing, and of other details of construction, 25 which will be understood by reference to the annexed drawing, in which—

Figure 1 is a plan of the entire structure in-section just above the wing-braces; Fig. 30 2 is a section showing the connection between the oscillating wall-levers and their connecting-rods; Fig. 3 is a plan showing the wings collapsed and folded in the center of the casing with the hinged walls in their 35 outer positions; Fig. 4 is a similar plan showing the wings folded at opposite sides of the spindle in the middle of the casing; Fig. 5 is a plan showing the wings collapsed, and moved to one side of the casing; Fig. 6 is an elevation of the revolving 40 door structure with the walls in their outer position; Fig. 7 is a cross section through the revolving door column just below the top of Fig. 9; Fig. 8 is an elevation in section where hatched through the top of the 45 revolving column; Fig. 9 is an elevation where hatched in section at its axis, through the bottom of the revolving column; Fig. 10 is a cross section through one of the 50 revolving wings showing the hand-rail attachments; Fig. 11 is an elevation of portion of a wing showing the hand-rail thereon; Fig. 12 is a plan showing the top of the outer end of a wing, in section, where

hatched, just above the packing keys; Fig. 55 13 is a vertical section through the top rail of a wing showing the sectional packing; Fig. 14 is a face view of the top outer corner of a wing, in section at the center line where hatched, showing connection between the 60 sectional packings upon the top and edge of the wing; Fig. 15 is a vertical section through a wing at the center of the brace-lock, with one end of the brace; Fig. 16 is a horizontal section through a wing and 65 brace-lock at the top of the pawls e^{10} ; Fig. 17 is an elevation of portion of a wing and the brace-lock, with the face of the lock partly broken away; Fig. 18 is an elevation of portion of a wing, showing the side of 70 the brace-lock, reverse to that shown in Fig. 16; Fig. 19 shows the edges of two door-wings in section where hatched, with the latch connecting the wings; Fig. 19^a shows face views of the two latch-plates; Fig. 20 75 is a plan of the roof of the door-casing; and Fig. 21 is a cross section, where hatched, on the dotted line $h-x$ in Fig. 20, at the center of the wall oscillator.

The central spindle or shaft d^5 for the 80 wings is shown swiveled at its upper end in a truck g^2 , a nut g^7 being screwed upon the top of the shaft, transmitting the weight to a ball-bearing g^6 which in turn rests upon a disk g^5 . (Fig. 21). An equalizing disk g^4 85 is interposed between the disk g^5 and the bottom plate of the truck g^2 , and pins g^8 and g^9 operate at opposite quadrants of the disk g^4 to form a species of universal joint, which permits the shaft to hang vertically if the 90 truck is not supported in a level position. The truck is supported upon the roof b^2 of the casing.

The wings are mounted to turn upon the shaft, the upper end of which is shown in 95 Fig. 8 and the lower end in Fig. 9, with a series of four cast iron disks at each end of the shaft upon which the inner edges of the wings are jointed.

The extreme lower and upper disks d^1 100 and d^9 are attached to the shaft to turn therewith, and one of the wings C' is jointed to these disks. The disk d^1 is keyed rigidly to the shaft and supports the weight of all the parts which hang thereon. Adjoining 105 these disks, are disks d^2 and d^8 , which are fitted to turn in contact with the shaft and connected by a sleeve d^{10} , and a second wing

C^2 is jointed upon these disks. Next these disks, disks d^3 and d^4 are fitted to turn upon the sleeve d^{10} and are connected by a sleeve d^{11} , and a third wing C^3 is jointed upon these disks. Disks d^4 and d^5 are fitted to turn upon the sleeve d^{11} , and are connected by a sleeve d^{12} , and the remaining wing C^4 is jointed upon these disks.

Construction of column.—The adjacent disks d^4 and d^6 are rabbeted externally to fit a shell d^{35} which is flush with the exterior of the disks. A short casing d^{38} is fitted movably upon the upper disk d^9 , and an annular felt packing d^{37} is secured between such casing and a flange upon an interior plate d^{36} . A collar d^{43} upon the hub of the disk d^9 supports a spring d^{39} to press the plate d^{36} , upward, thus keeping the packing d^{37} constantly against the roof b^2 of the revolving door. An additional shell d^{29} is fastened to the bottom of the disk d^1 and extends close to the floor so that the disks and supplemental shells form a continuous cylindrical column to contact with the inner edges of the wings, or with packings thereon.

The lower end of the shaft d^5 does not extend to the floor, but is furnished with a socket-casting d^{23} which is adjustable vertically upon the shaft, and is provided at the bottom with a pin d^{25} . This pin can be lifted out of its floor-step d^{26} when it is desired to move the collapsed wings to one side of the door-casing, to form an open passageway through the center of the same. When the pin d^{25} is in its step the socket-casting is stationary. A circular flange d^{28} is secured in the bottom of the shell d^{29} to center it, and is fitted loosely to the casting d^{23} to revolve around the same when the casting is stationary.

A circular plate d^{24} with incurved flange at the periphery is swiveled upon the socket-casting, and a latch d^{31} is attached to the disk d^1 to engage this flange, and holds the socket-casting raised and the pin clear from its step, when moving the collapsed door sidewise. When thus moving the door, the wings are disposed equally at opposite sides of the column as shown in Fig. 4, and such disposition is secured automatically by locking the disks d^1 and d^2 together before the wings are folded. This is effected, as shown in Fig. 9, by a bolt d^{33} extended through a mortise in the disk d^1 and its upper end adapted to engage a slot e^{33} in the adjacent side of the disk d^2 . The opposite wings C^1 , C^3 , are attached to the disks d^1 and d^3 , and when the wings are all extended in their working position, as in Fig. 1, the slot e^{33} coincides with a bolt d^{33} .

The bolt is automatically raised when the socket-casting is lifted, by means of a foot d^{32} upon the bolt, having a roll d^{34} to rest upon the circular plate d^{24} . The mere lifting of the socket-casting, before the wings

are collapsed, thus secures two wings at opposite sides of the center, against which the intermediate wings are readily folded. When it is desired to restore the wings from the side of the door-casing to the center, in their operative position, the pin d^{25} is brought over the floor-step d^{26} , and the latch d^{31} is released by inserting the hand through the opening d^{30} , thus allowing the socket-casting to drop.

The pin d^{25} is preferably made with a screw-thread, as shown in Fig. 9, to worm out of the step the dirt which falls within the same when not filled by the pin, and the bottom terminal of such screwthread is shaped to embrace a stud d^{27} in the bottom of the step, which holds the socket-casting thereafter from turning. Such stationary socket-casting then forms an extended bearing for the bottom end of the shaft d^5 , which bearing can be kept lubricated and thus greatly diminish the resistance to the rotation of the column.

Joint of wings and column.—Figs. 7 and 8 show the joint of the wings and column which permits them to turn as a unit about the shaft until the wings interfere with one another, and thereafter to turn upon their joints, with the disks, when the wings are folded together. One side of each disk has an opening to admit a hinge-ear, and a transverse groove is formed upon the disk at each side of such opening. The inner edge of each wing is provided with a joint-casting d^{13} having at the center a hinge-ear d^{14} which fits into the disk-opening, and at opposite sides of the hinge-ear are hinge-lugs c^8 which fit the said grooves when the wing is extended from the disk. The lugs c^8 are pressed forcibly and elastically into the grooves by mechanism within the disk, consisting of springs d^{20} which are mounted upon U-shaped frames d^{15} and d^{16} , the former of which is connected to the hinge-ear d^{14} by a link d^{14} . This link is connected to the frame by a pin d^{18} and to the hinge-ear by a pin d^{40} . The frame d^{15} would not appear in Fig. 8, but the lugs on that frame, which embrace the rods d^{21} are shown sectioned, and the remainder of the frame is indicated by dotted lines to show its location.

The frame d^{16} is held adjustably within the disk by a screw d^{17} which adjusts the tension of the springs. The frame d^{16} has lugs d^{41} upon its two ends, with rods d^{21} fitted therein and springs d^{20} mounted upon the rods. The frame d^{15} , as shown in Fig. 9, lies above the springs and has lugs projected downwardly, which also engage the rods d^{21} , so that the springs are compressed between the lugs upon these two frames.

The tension of the springs holds the door-wing firmly to the disk, so that the disk turns with the wing until the adjacent edges

of two wings collide, after which the wing turns upon one of the hinge-lugs c^8 , drawing the hinge-ear d^{19} out of the disk in opposition to the resistance of the springs. (See 5 dotted wings at right of Fig. 7.) When the wings are thus collapsed, they may be held together by an automatic latch shown in Figs. 19 and 19^a, the parts of which are located close to the edges o of the wings so as to be accessible when it is desired to unlatch 10 the wings. Each wing is provided upon one side, as shown in Fig. 19, with the movable latch-hook i , and upon the opposite side with a plate l having a lip m to engage a sloping head k upon the latch-hook. The 15 latch is pivoted within the wing upon a plate k' . The lip m , as shown in Fig. 19^a, is made many times wider than the hooked head k , so that the latch may engage the same when the edges of the wings are even 20 with one another, as shown in Fig. 4, or uneven with one another, as shown in Fig. 3.

A knob or pin n is projected from the latch-head to the edge o of the wing, to lift 25 the latch when it is desired to release the wings from one another.

Brace-lock for doors.—A brace-lock is fitted in each wing, extending preferably through the same, and each brace has a 30 permanent swivel attachment to the side of the lock on one face of the door, and a detachable spring connection with the opposite side of the lock. The swivel connection consists of a rotatable block p upon the 35 lock-casing e^8 , with the head p^1 of the brace e^1 pivoted therein, so that it may hang down when not in use, as indicated by the dotted lines p^3 in Fig. 18. The opposite end of the brace has a head p^2 with lugs or rolls q at 40 its opposite sides which enter the lock casing e^7 to engage dogs therein and ledges r which have inlets at their opposite ends to admit the lugs. Sloping seats r^1 are provided within the inlets, leading the lugs to 45 the faces of dogs s , s^1 which are pivoted in separate frames t , t' arranged to slide within the lock-casing E . A space w is shown between the ledges r in Fig. 17 to admit the head p^2 of the brace as the lugs q pass beneath the ledges. The dogs are forked, as 50 shown at the left hand end of Fig. 17, to engage the lugs at opposite sides of the head p^2 . Leaf-springs t^2 press the dogs normally toward the ledges r and the dogs are 55 constructed with a space between their adjacent ends sufficient to admit the lug q upon the head of the brace. The frames t , t' overlap one another at the sides, as shown in Fig. 17, and have opposed lugs u between which spiral springs v are inserted 60 under compression.

The frames are prevented by the contiguity of the seats r^1 from moving toward one another, thus preserving the space between the ends of the dogs for the admis-

sion of the lugs or rolls q ; but either frame may be pulled away from the other in opposition to the springs v , as indicated by the dotted lines t^2 in Fig. 17. The dogs are so shaped that when moved back, they 70 slide beneath the seats r^1 to release the lug q , as dotted at the right in Fig. 16. When the head of the brace is pressed into either of the inlets it forces the adjacent dog downwardly, and the lugs q pass beneath the 75 ledges r into contact with the other dog. The lugs thus become locked between the two dogs and the ledges, and can be released manually by putting the finger in the inlet and pressing one of the dogs down to 80 release the lugs. Either a push or pull upon the brace also operates to release it from the lock, as it moves one or the other of the dogs with its frame t or t' until the lugs upon the brace reach the inlet, as shown 85 by the dotted lines q^1 in Fig. 16, when the head of the brace pulls freely out of the lock.

When the wings are connected by the braces for operation as shown in Fig. 1, the springs v exert sufficient resistance to the 90 escape of the braces from the locks, to rotate the door-wings in a normal manner, but if two adjacent wings are pushed in opposite directions, the tension of the spring is overcome and the head of the brace pulls 95 out of the lock. Such release is effected by pulling, but if in case of a panic a number of people were to crowd into or against the revolving wings, the pressure upon the wings would disengage all the braces by 100 the push upon them, thus allowing the wings to fold together and clear the passage. Any brace when disengaged falls down, as indicated by dotted lines p^3 in 105 Fig. 18, and is thus out of the way until used for reengagement.

The rigid braces described serve, if one be accidentally disengaged, as by wind pressure upon one of the wings, to hold the remaining wings in place until such brace 110 can be reengaged, which avoids the passage of dust and wind through the casing which sometimes happens where flexible braces are used and one of them becomes disengaged; as such disengagement permits all the wings 115 to collapse together, thus opening the passage to wind and dust. My braces and locks are so constructed that they may be used on any of the revolving doors now in use.

Oscillating of side-walls.—The hinged side-walls a^1 , a^8 , a^4 and a^5 are moved to just clear or contact with the outer edge of the revolving wing, by means of a cam h^1 upon the top of the shaft a^6 .

In Fig. 20, the roof b^2 of the door-casing is broken away at one side to show the hinged walls beneath the same.

The truck has wheels g^3 to run upon rails g^1 upon the roof when shifting the wings to 130

one side of the casing, a slot being provided between the rails for the movement of the shaft at such times.

The movable walls are jointed by hinges a^8 at their inner edge to a post a^2 upon the door-frame a^7 , and each side-wall is hinged by a bracket h^5 and pin h^6 to a connecting-rod h^4 which is jointed to a lever h^8 , and this lever has an arm carrying a roll h^2 to bear upon the cam. The two rolls at one side of the cam bear one above the other upon the same part of the cam, so as to similarly oscillate two adjacent side-walls. The levers are pivoted upon pivot studs h^{21} fixed on plates h^{16} upon the roof b^2 at opposite sides of the cam. Means is provided to vary the effect of the cam upon the levers so that when desired the side-walls may, by a diminished vibration, clear the edges of the door-wings, to permit ventilation through the door-casing.

Four levers are shown to operate the four side-walls, but only the outer ends of the levers in the left hand part of Fig. 20, are shown, in order to expose the means for varying the stroke of the levers. Such means consists of levers h^{14} having fulcra h^{28} upon one end of the plates h^{16} , each lever supporting a stud or roll h^{15} between the studs h^{27} . Each lever h^{14} carries a pin h^{30} from which a spring h^8 is extended to a pin upon the lever h^3 . The spring operates on the said lever h^3 and through that upon the connecting-rod h^4 to draw the side-walls normally toward the door-wings, at the same time pressing the rolls on the lever-arms h^2 toward the cam. The cam has four equal projections which operate synchronously upon the four door-wings by pressing the connecting-rods h^4 outwardly, in opposition to the springs h^8 , thus moving the walls in the desired manner for the passage of the wings. The levers h^{14} are connected at their outer ends by swivel-nuts h^{17} and a right and left hand screw h^{18} . Fingers h^7 are projected one above the other from the hubs of the levers h^8 , and lie normally in contact with the stud or roll h^{15} when the side-walls are moved inward to the maximum extent required. See the upper half of Fig. 20.

Fingers h^7 are fitted loosely to the pivot-studs h^{21} of the levers h^8 , and lie normally in contact with the stud or roll h^{15} when the side-walls are moved inward to the maximum extent required. Each finger has a hub upon its lower side to support them one above the other, and the levers h^8 are provided with downwardly projecting brackets h^{31} to contact with the outer sides of the fingers, as the side walls move inwardly, so that the inward movement of the side walls is controlled by the fingers; while the outward movement of the walls is wholly independent of the fingers.

The adjusting of the roll or stud h^{15} outwardly obstructs the inward movement of the fingers as the walls move inwardly, and thus causes the side-walls to clear the door-wings in their revolutions, and the following means is provided to vary such clearance to any desired extent. The screw h^{18} is mounted in bearings upon a plate h^{27} , and has a worm-wheel h^{19} upon its middle to which a worm h^{20} is fitted, with a shaft h^{22} extended over the top of the post a^8 . An upright shaft h^{24} is mounted upon the post and connected by bevel-wheels at the top with the shaft h^{22} , and is connected at the bottom to a hand-wheel h^{26} by gearing in a crank-box h^{25} . By turning this hand-wheel, the levers h^{14} can be actuated to adjust the rolls h^{15} toward the fingers h^7 as desired, so as to prevent the side-walls more or less from swinging inward to their fullest extent, thus leaving some opening, when desired, by which air can pass through the casing to ventilate the apartment in mild weather.

If anyone is caught between the side-walls and the door-wing, the pressure upon his body would be limited to the pressure of the spring h^8 , which is the force that moves the side-walls inwardly, but special provision is also made to release the side-walls entirely from the grip of the spring in case of such accident, such provision consisting of an automatically detachable connection, shown in Fig. 2, between the rod h^4 and the end of the lever h^3 . The lever is forked, and the end of the rod is formed with a slot h^9 , and fitted into the fork, as shown in Fig. 2, and the detachable connection is formed by a pin h^{10} having a conical shoulder fitted into a conical recess or countersink upon the rod, at the inner end of the slot.

A socket-tube h^{13} is extended from the upper side of the fork to receive the head of the pin and a spring h^{11} , and a thumb-screw h^{12} is provided to adjust the pressure of the spring so as to hold the conical shoulder into the countersink with force sufficient to oscillate the doors under normal conditions.

Any excessive pressure upon the side-walls pushes the conical shoulder of the pin upwardly and permits the rod to slide upon the lower end of the pin which passes through the slot, the length of the slot being sufficient to permit the side-wall to push back as far as is desired.

Door-wing packings.—Sectional packings are formed of spring-keys or fingers sustained upon the vertical and upper edges of the door-wings, to take the place of the ordinary rubber-flap, which wears with great rapidity and soon loses its elasticity so that it does not make a close joint with the side-walls of the door-casing. Such packings are shown in Figs. 12, 13 and 14, and consists of fingers j^4 , j^5 , jointed upon a hinge j^3 .

rod j^3 which is journaled in bearings or tongues j^{16} formed upon a carrier j^1 ; which carrier is held detachably upon the edge of the door-wing so that it can be removed at pleasure with all of the hinged fingers.

The carrier, as shown in Fig. 12, consists of a sheet-metal trough adapted to fit upon the edge of the door-wing, and having the tongues j^{16} punched from its back at suitable intervals to embrace four or six of the fingers, thus giving the rod j^3 a strong support. The carrier j^1 is held detachably upon the edge of the wing by clips j^2 which are constructed to pass freely through the slots 15 from which the tongues j^{16} are passed, and are offset at the upper end so that when screwed upon the edges of the door-wing at intervals their offset ends slip over the back plate of the carrier and hold it close 20 upon the edge of the wing, while permitting it to be removed by sliding it upwardly off the ends of the clips.

The outer ends of the fingers have undercut notches to receive a continuous packing-strip of fabric j^9 which contacts with the casing-walls and also holds the fingers together flexibly. The alternate fingers are provided with curved leaf-springs j^7 arranged to press such fingers in opposite directions, the strip j^9 preventing the fingers from yielding to such pressures, and the resultant of the pressures holding the fingers normally in a central position, projected from the edge of the door. The hinged rod 35 is grooved longitudinally and a segmental recess j^{20} is formed in the hub of each finger with shoulder at one end, and hooks are formed upon the ends of the curved leaf-springs to engage such grooves and shoulder. 40 The segmental recesses are formed at opposite sides of the hub in the alternate fingers j^4 and j^5 , and the springs are applied thereto in reverse positions to produce the effect described above of holding the fingers centrally; half of the springs being compelled 45 to yield when the fingers are swung in one direction or the other, by the contact of the cord j^9 with the casing-wall. When all the fingers are thus swung, the hooks upon half 50 of the fingers move freely in the segmental recesses j^{20} , which avoids all strain upon the springs of such fingers. The eye in the hub of each finger is materially larger than the hinge-rod j^3 , to limit the spring j^7 and permit its movement and in practice the springs 55 are placed in such eyes, and a washer crowded into the eye at each side of the spring to hold it in place, before the fingers are threaded upon the hinge-rod.

In assembling the parts, one end of the hinge-rod is inserted in the first tongue j^{16} and through a group of four fingers between such tongue and the next, the rod being so held that the groove engages the hooks upon 60 the inner ends of the springs j^7 . The hinge- 65

rod is thus slipped through all of the tongues and fingers in succession, the springs causing the alternate fingers to project at opposite inclinations from the center line. When the rod is wholly inserted, the packing-strip j^9 , 70 which may be a molded section of felt, rubber-cloth or any suitable fabric, is slipped successively into the notches in the outer ends of all the fingers, each being brought to the center during such operation so that 75 the cord holds them all elastically in place. The joining of the fingers by such a flexible strip permits any part of the packing to yield independent of the rest.

With the construction described, the fingers are adapted to yield sufficiently to compensate for any inequalities in the surface of the casing-walls, and the construction is far more durable than a flexible flap, as its elasticity is permanent, while there is no 85 wear upon it except at the strip of fabric j^9 , which can be readily and cheaply renewed. The packing for the horizontal top edge of the door-wings is not hinged, but consists of a trough j^{14} inserted in a groove in the top 90 of the wing and having inwardly bent flanges upon its inner edges, with blocks j^{13} held movably therein, beneath certain of which blocks springs j^{15} are inserted in the bottom of the trough, to hold them normally 95 at a uniform level. The tops of the blocks are formed with undercut grooves, and a flexible packing-strip j^9 is engaged with such grooves, so that the blocks pressed upwardly by the springs serve to lift all the other 100 blocks equally. At the upper corner of the wings the two packings are united by plates j^{10} adapted to clamp between their edges the ends of the two flexible cords j^9 , and the plates arranged to pivot upon the hinge-rod 105 j^3 and to embrace the upper hinged finger so as to swing therewith. The series of fingers does not extend to the top corner of the wing, but room is left for a block j^{11} upon one of the plates j^{10} to fit upon the top of the 110 hinge-rod j^3 to swing thereon. The plates are clamped together by screws, as shown in Fig. 14, and springs j^2 resting upon the upper finger serve to press the block and plates normally upward like the blocks j^{13} . 115 The corner packing thus has an upward movement like the packing upon the top of the wing, and a capability of swinging on the hinge-rod like the packing on the edge 120 of the wing.

A packing is provided, as shown in Fig. 7, to make a close joint between the inner edges of the wings and the central post, all the parts of which form a cylindrical surface of uniform diameter. This packing consists of a longitudinal strip c^8 of yielding material having its opposite edges fitted beneath flanges turned inwardly upon the edges of a metallic strip which is secured 125 upon the inner edge of each wing. This 130

metallic strip with inturned flanges forms a grooved metal holder and the flexible packing strip is made a little wider than the space between the flanges on the metal holder, so that it bulges toward the cylindrical surface of the post and forms at all times an elastic contact with the same when the wings are in a radial position. Such packing strip is secured in the holder only by friction, and may therefore be detached and renewed whenever required.

Hand-rails upon wings.—To afford a considerable projection of the hand-rails from the faces of the door-wings without preventing their folding close together when the wings are collapsed, the hand-rails f^1 are hinged upon links f^4 and f^6 , as shown in Figs. 10 and 11, which links are jointed to bearings upon the door-wing. The bearings f^{11} for the outer end of the rail are carried by a foot f^8 , and the links have pivots f^{15} fitted to such bearings. The rail is provided at its inner end with an extension f^9 projected nearly to the central drum, and the adjoining door-wing has a plate thereon with an upwardly beveled lug f^{10} adapted to contact with such extension when the wings are swung toward one another. The links f^6 are formed in a swinging frame having pintles jointed in bearings f^{12} upon a foot-plate f^7 . The lower bearing has a notch f^{16} to which a beveled tooth upon the link-frame is fitted, and the upper bearing has socket f^{14} with a spiral-spring f^{13} therein, and the pintle at that side of the link-frame has a sleeve fitted into such socket so as to either turn or slip upward therein. The ends of the spring are engaged respectively with the cap of the socket and with the bore of the sleeve, so that the spring presses the link-frame normally downward, and thus engages the tooth with the notch f^{16} of the lower bearing f^{12} . The beveled lug f^{10} , when it contacts with the extension f^9 of the hand-rail, operates first to raise the same, thus lifting the tooth on the link-frame out of the notch f^{16} , and then forcing the rail endwise, so as to swing upon its links into close contact with the door-wing, as shown in dotted lines in Fig. 10. Such swinging winds up the spring f^{13} , so that when the door-wings are again separated, the spring throws the hand-rail back toward its initial position until the tooth upon the link-frame enters the notch f^{16} in its bearing, which serves to hold the hand-rail firmly in position when used in pushing the door.

Having thus set forth the nature of the invention what is claimed herein is:

60 1. In a revolving door, the combination, with the central shaft, of similar series of disks near its opposite ends with concentric sleeves connecting the disks in pairs and the wings hinged each to one pair of the disks, whereby the wings in collapsing first turn

the disks around the shaft until the wings interfere and then turn upon their hinged connections to the disks.

2. In a revolving door, the combination, with the central shaft, of similar series of disks near its opposite ends with concentric sleeves connecting the disks in pairs, wings hinged each to one pair of the disks, and springs for holding the wings normally radial to the disks. 75

3. In a revolving door, the combination, with the central shaft, of similar series of disks near its opposite ends with concentric sleeves connecting the disks in pairs, wings hinged each to one pair of the disks, and 80 spring fixtures within the disks with connection to the wings to hold them normally radial to the disks.

4. A revolving door having a central shaft with similar series of disks near its opposite ends and concentric tubes connecting the same in pairs, a series of wings each having connection to the two disks upon one sleeve, such connection with each disk having hinge-lugs at opposite corners of the wings 90 next the disk, and the disk having open grooves across the rim of the disk to receive such lugs, and an opening between such grooves, a hinge-ear projected from the wing through such opening into the disk, 95 and a spring fixture within the disk engaging such ear to hold the wing normally radial upon the disk.

5. In a revolving door, the combination, with the central shaft, of similar series of 100 disks near its opposite ends with concentric sleeves connecting the disks in pairs, a shell engaging the shaft between the disks, and wings jointed upon the disks to turn thereon and arranged to contact continuously with 105 all of the disks and the shell.

6. In a revolving door, the combination, with the central shaft, of similar series of disks near its opposite ends with concentric sleeves connecting the disks in pairs, a shell 110 engaging the shaft between the disks, and wings jointed upon the disks to turn thereon, a longitudinal grooved metal holder upon the inner edge of each wing, and a flexible packing strip fitted detachably in 115 the said holder to contact uniformly with all of the disks and the shell when the wings are extended.

7. In a revolving door, the combination, with a central post, of wings hinged thereon, springs for holding the wings normally radial to the post, and the adjacent faces of the wings provided near their edges with engaging members consisting of the movable latch-hook k with means at the edge of 125 the door for lifting such hook, and the opposed plate having a lip m much wider than the latch-hook to engage therewith when such engaging parts are not centrally opposed to one another, the latches upon the 130

wings serving automatically to lock all the wings to one another in opposition to the springs, when folded together at one side of the post in any part of the casing.

5 8. In a revolving door, the combination, with the central shaft, of a series of wings collapsible about said shaft to one side of the shaft, a brace-lock upon each of the wings having upon one side a swivel attachment for a brace and on the opposite side a doubly detachable connection for a brace, such connection operating to detach the brace by pushing or pulling, whereby pressure applied to a door-wing pulls the brace from the adjoining wing, and continued pressure thereafter detaches the braces successively from the remaining wings by the push upon said braces.

9. The combination, with the central 20 shaft, and a series of wings collapsible about said shaft to one side of the shaft, of a brace-lock upon each of the wings having opposed sloping inlets upon one side with ledges between the said inlets, and spring-dogs beneath the inlets with space between the same for lugs upon a brace, yielding supports for the dogs, permitting movement of the same toward the inlets, and braces attached at one end to each of the 25 door-wings and having at the opposite end lugs to enter the inlet and engage the ledges and the opposite ends of the dogs, the construction permitting the escape of the brace-lugs from the inlets when the brace is either 30 pushed or pulled.

10. The combination, with the central shaft, and a series of wings collapsible about said shaft to one side of the shaft, of a brace-lock upon each of the wings having opposed sloping inlets upon one side with ledges between the said inlets and spring-dogs beneath the inlets with space between the same for lugs upon a brace, independent frames movable within the lock-casing and having the dogs pivoted therein, and a spring connection between the frames whereby a thrust upon either of the dogs moves the said dog toward the inlet in opposition to the spring.

50 11. The combination, with the central shaft, of a series of wings collapsible about said shaft to one side of the shaft, braces attached to the same side of each of the wings and their free ends shaped to engage a brace-lock, a brace-lock upon each of the wings having a doubly detachable connection for the shaped ends of the braces, the brace-locks having spring-sustained means to retain such shaped ends when moved against a specific spring resistance, and operating to discharge such shaped ends when the pressure in either direction exceeds such spring resistance.

12. A revolving door, having a revolving 65 shaft, and wings carried thereby, with a

casing having hinged side-walls movable at their extremities, and means operated by the spindle for vibrating the side-walls at each passage of a wing to maintain contact therewith.

5 13. A revolving door having a revolving shaft, and wings carried thereby, with a casing having hinged side-walls movable at their extremities, a cam upon the revolving shaft, and levers operated by the cam with 70 connections to the side-walls to vibrate the same as required.

14. A revolving door having a revolving shaft and wings carried thereby, with a casing having hinged side-walls movable at 80 their extremities, springs for pressing the side-walls normally inward toward the shaft, a cam upon the revolving shaft, levers operated by the cam, and slotted connections to the side-walls adapted to vibrate the side-walls and to permit their outward movement independent of the levers.

15. A revolving door having a revolving shaft and wings carried thereby, with a casing having hinged side-walls movable inward toward the shaft, a cam upon the revolving shaft, levers operated by the cam with connections to the side-walls to vibrate the same, adjustable springs for pressing the side-walls toward the shaft, and means 90 for releasing the spring pressure when desired, to leave the walls in their outward position.

16. A revolving door having a revolving shaft, and wings carried thereby, with a casing having hinged side-walls movable at their extremities, a cam upon the shaft with levers operated thereby, adjustable stops for varying the extent of the lever movement, and connections from the levers to the side 105 walls to vibrate the same.

17. A revolving door having a revolving shaft, and wings carried thereby and collapsible thereon, with a casing having hinged side-walls movable at their extremities, track-rails sustained above the wings, a truck having a bearing for the shaft above the wings and fitted movably to the said rails, a cam upon the shaft above the truck, and levers moved by the cam with connections to the side-walls, the outward movement of the side-walls clearing the levers from the cam to permit the truck, shaft, and collapsed wings to be moved to one side of the casing.

5 18. In a revolving door, the combination, with each of the wings, of hand-rail-bearings having links jointed thereto and projected from the face of the wing, and a hand-rail jointed to such links and one end extended in the path of the adjacent wings as the wings are folded together, whereby the hand-rail is pushed longitudinally and swung close to its supporting wing.

19. In a revolving door, the combination,

with a wing, of a hand-rail connected to the face of the wing by projecting jointed links, and means upon the adjacent wing for pressing such hand-rail longitudinally when the wings are folded toward one another, to swing such hand-rail close to its supporting wing.

20. In a revolving door, the combination, with the casing, the central shaft, the wings carried thereby and a step below the shaft, of a center-pin adjustable vertically upon the bottom of the shaft and having a spiral groove to lift the dirt from the step by rotation therein.
21. In a revolving door, the combination, with the casing, the central shaft, the wings carried thereby and a step below the shaft, of a tubular pin-carrier movable vertically upon the bottom of the shaft, a center-pin upon the carrier to enter the said step, and means swiveled upon the carrier for holding the carrier elevated when desired.

22. In a revolving door, the combination, with a central column having a shaft connected to revolve therewith and suspended from an overhead truck, of a socket-casting forming a bearing for the bottom of the shaft and vertically movable within the bottom of the column, such socket-casting having a pin to fit a floor-step and remain stationary therein, and means to raise the

socket-casting from the step, and to retain it in such raised position when moving the collapsed wings to the side of the casing.

23. In a revolving door, the combination, with the central shaft suspended from an overhead truck, of similar series of disks near its opposite ends with concentric sleeves connecting the disks in pairs, wings hinged each to one pair of the disks, column-shells applied to the disks to form a continuous cylindrical column, a socket-casting forming a bearing for the bottom of the shaft and vertical movably within the bottom of the column, such socket-casting having a pin to fit a floor-step and remain stationary therein, a vertical bolt extended through the bottom disk to engage a slot in the one above, a connection between such bolt and the socket-casting, and means for holding the socket-casting lifted within the casing and thus actuating the bolt during the shifting of the collapsed doors to the side of the casing.

In testimony whereof I have signed my name to this specification in the presence of two subscribing witnesses.

WALTER S. ELY.
